[57] CLAIM

The ornamental design for a keyboard for electronic accordion, as shown and described.

DESCRIPTION

FIG. 1 is a front, top and right side perspective view of a keyboard for an electronic accordion showing my new design;

FIG. 2 is a front elevational view;

FIG. 3 is a top plan view;

FIG. 4 is a rear elevational view;

FIG. 5 is a bottom plan view;

FIG. 6 is a right side elevational view;

FIG. 7 is a left side elevational view;

FIG. 8 is a top plan view of a second embodiment of a keyboard for an electronic accordion showing my new design wherein the upper left group of controls is different from that of the other embodiment.

FIG. 9 is a front elevational view thereof; and

FIG. 10 is a rear elevational view thereof.

A rear elevational view, a bottom plan view, a right side elevational view and a left side elevational view of the keyboard of FIG. 11 correspond to FIGS. 4, 5, 6 and 7, respectively.
